VALVE

Norman S. McEwen, Fort Lauderdale, Fla., assignor to Helpy Selfy Service System, Inc., Fort Lauderdale, Fla., a corporation of Florida

Application May 2, 1945, Serial No. 591,477

2 Claims. (Cl. 137—34)

1

This invention relates generally to valves, and more particularly to flap valves, having for its object to provide a construction which is simple in parts and operation, and more positive in actuation than those heretofore proposed.

With these and other objects in view, the invention resides in the novel details of construction and combinations of parts as will be disclosed more fully hereinafter and particularly covered by the claims.

Referring to the accompanying drawings forming a part of this specification and in which like numerals designate like parts in all the views,

Fig. 1 is a side elevation of the valve as applied to a container;

Fig. 2 is a rear elevation of the valve;

Fig. 3 is a bottom plan view of the valve;

Fig. 4 is a vertical sectional view illustrating in full lines the valve in closed position, and illustrating in dotted lines the valve in opened position; and

Figs. 5 and 6 are views illustrating modifications of the construction shown in Fig. 4.

The valve of this invention obviously is capable of application to many structures but, for the purpose of exemplification only, it is here illustrated and described in connection with the outlet or drain of the tub of a washing machine.

The valve generically comprises two members, a conduit through which a fluid may pass, and a closure for one end of the conduit, the closure having hinged, rocking, and/or pivotal relation with the conduit and under spring tension with respect thereto, the tension being such that said closure will be maintained either in tight closed or in full opened position upon proper manipulation of said closure. More specifically, and with reference to the drawings, the conduit is identified generally by the numeral 2, and the closure by the numeral 3, while 4 denotes a spring for creating tension therebetween.

The conduit preferably comprises a cylindrical member which is threaded or otherwise secured to the end of the drain 5 of the tub of a washing machine. The free end of the conduit is suitably finished to form the seat for the customary disc washer 6 carried by the closure 3 by virtue of a central perforation in the washer receiving therethrough the screw 7 as illustrated in Fig. 4, or the headed post or "button" 8 formed integrally with the closure as shown in Fig. 5. The screw 7 is recommended when relatively rigid washers are used, whereas the "button" construction is preferred for quick attachment and detachment of yieldable and relatively soft washers

such as those made of rubber or other material capable of stretching over the "button."

The conduit carries a tongue 10 externally thereof, disposed in a central longitudinal plane of the conduit, which tongue is relatively closely straddled by a pair of parallel fingers 11 and 12, constituting a fork, carried by and extending rearwardly of the closure 3. This interfitting relationship of tongue and fingers is maintained 10 in each of the modifications illustrated, Fig. 5 showing a pivot pin 13 passing through the overlapping portions and providing the hinged relation referred to hereinbefore.

The coil spring 4 is looped upwardly and over 15 an upper portion of the tongue, the ends of the spring passing beneath the closure and secured thereto in any convenient manner as by engagement with a hook 14 as illustrated for quick attachment and detachment. A concave seat 15 or other suitable formation is provided on the tongue and/or on the conduit for reception and retainment of the looped portion of said spring.

In the modification illustrated in Figs. 1 to 4 the under surface of the tongue is provided with 25 a notch or socket 16 or equivalent construction adapted to receive a relatively thin edge 17 constituting a fulcrum, said edge formed substantially at the juncture of the parallel fingers 11 and 12 with the closure 3, said fulcrum being 30 disposed substantially midway between the ends (such as 18) of the fingers and the forward extremity of the closure. A hole 19 or equivalent construction is provided at the end 18 of one or both of the fingers, for receiving one end of an 35 operating rod 20 or other device by which the closure is rocked about its fulcrum 17 to open and close the valve.

In the modification illustrated in Fig. 6 the 40 same general principles are present, the chief difference in construction being the omission of the positive, relatively closely confining or restricted socket or notch 16, the tongue 10 at this point having a broader under surface upon which the fulcrum edge 17 is free to ride. The upward extensions of the fingers 11 and 12, constituting the ears indicated by the numeral 30, have their forward edge surfaces 31 rounded, or so formed arcuately that they will abut and roll upon the 45 rear external cylindrical surface of the conduit 2 as the valve closure member 3 is actuated. If desired a wire, bolt, pin or rivet 32 may be disposed in the lower extremity of the tongue 10 as a safeguard against its displacement with reference to the fork comprising the fingers 11 and

12, in a manner similar to the formation of the T head 33 shown in Figs. 1 to 4.

The positions of the hook 14, the seat 15, and the fulcrum-socket, as well as the throw or movement of the operating rod 20, are made such that when said rod is moved to its limit in one direction the spring 4 will be disposed to one side of the fulcrum, with the closure 3 in tight engagement with the conduit to maintain the valve closed, whereas when said rod is moved in the opposite direction the spring will be moved to a position on the other side of the fulcrum to keep the valve open, all as will be readily understood.

The metal at the juncture of the fingers with the closure 3 is ground or otherwise formed to produce the surface 25 terminating in the aforementioned fulcrum edge 17, and the tongue 10 is provided with an under surface 26, the planes of these two surfaces being such that, when the operating rod is moved to open the valve and the spring 4 has moved past the fulcrum 17, the surface 25 of the closure will abut the surface 26 of the tongue and prevent further opening movement of the valve. According to the modification shown in Fig. 5 the equivalent surfaces 27 and 28 are provided for the same result.

It is obvious that those skilled in the art may vary the details of construction and arrangements of parts constituting this invention without departing from the spirit thereof, wherefore it is desired not to be limited to the exact foregoing disclosure except as may be required by the claims.

What is claimed is:

1. A valve comprising a conduit and a closure for one end thereof, said conduit provided with a tongue extending laterally therefrom, the uppermost surface of said tongue having a spring receiving groove formed therein, the lower portion of said tongue having an inwardly directed surface constituting a seat and upon which the closure has contacting oscillatable movement, said closure provided on its under portion with a hook and on its upper portion with a washer for engaging the end of said conduit, said closure further provided with a pair of substantially parallel fingers closely straddling said tongue, the inner ends of said fingers terminating in a wall having a thin upper edge constituting a fulcrum

contactingly engaging the seat of said tongue and about which fulcrum the closure is oscillated by a force applied through said fingers, and a coil spring for maintaining said fulcrum in coengagement with said seat, said spring having its mid-portion bodily seated in said groove and having its opposite end portions extending downwardly on opposite sides of said tongue with the extremities of said spring removably engaging said hook.

2. A valve comprising a conduit and a closure for one end thereof, said conduit provided with a tongue extending laterally therefrom, the uppermost portion of said tongue formed as a spring receiving pocket, the lower portion of said tongue having an under surface constituting a seat and upon which the closure has contacting oscillatable movement, said closure provided on its under portion with a projection and on its upper portion with a washer for engaging the end of said conduit, said closure further provided with a pair of substantially parallel fingers closely straddling said tongue, the inner ends of said fingers interconnected by a wall having a thin upper edge constituting a fulcrum contactingly engaging the seat of said tongue and about which fulcrum the closure is oscillated by a force applied through said fingers, and a coil spring for maintaining said fulcrum in coengagement with said seat, said spring having its mid-portion bodily seated in said pocket and having its opposite end portions extending downwardly on opposite sides of said tongue with the extremities of said spring removably engaging said projection.
